UNITED STATES PATENT OFFICE.

GEORGE W. HASKELL, OF PHILADELPHIA, PENNSYLVANIA, ASSIGNOR TO
GEORGE W. HASKELL, WILLIAM H. HASKELL, AND HENRY J. HASKELL,
OF SAME PLACE.

THILL-COUPING.

SPECIFICATION forming part of Letters Patent No. 279,381, dated June 12, 1883.

Application filed April 30, 1883. (No model.)

To all whom it may concern:

Be it known that I, GEORGE W. HASKELL, a citizen of the United States, and a resident of Philadelphia, Pennsylvania, have invented 5 certain Improvements in Thill-Couplings, of which the following is a specification.

My invention relates to improvements in thill-couplings of the same general character as those shown in my prior Patents No. 185,528, 10 December 19, 1876, and No. 205,082, June 18, 1878, the present improvements comprising certain details in the construction of the coupling with the view of simplifying the construction of the same and increasing its efficiency.

15 In the accompanying drawings, Figure 1 is a side view of my improved thill-coupling, the axle being in section; Fig. 2, a longitudinal section of the coupling; Fig. 3, a perspective view of the parts of the same detached from 20 each other; Fig. 4, a sectional plan view on the line 1 2, Fig. 1; Fig. 5, a transverse section on the line 3 4, Fig. 2; and Fig. 6, a detached view of one form of pivot-bolt.

A represents the axle of the vehicle, and B 25 one of the shafts or the pole of the same, to which is secured the usual thill-iron, D, having an eye, a.

To the axle is secured the usual clip, E, having ears b b, in which are openings for the reception of the pivot-pin d, which passes through 30 the eye a of the thill-iron, the latter fitting snugly between the ears b of the clip, as shown in Fig. 4. A block, F, is also fitted between the ears b, and is supported in position vertically by means of lugs e e, resting on said ears, the block being recessed for the reception of 35 the eye a, against which it bears at and near each end, as shown in Fig. 4. The block F projects below the ears b, and to this projecting portion of the block is hung on each side a lever, G, the upper or long arms of these levers being notched for adaptation to the grooved projecting ends of the pivot-pin d, so that when the levers are in the position shown 40 in Fig. 1 the lateral removal or displacement of said pin or spreading of the ears b is impossible.

In the projecting lower portion of the block F are formed grooves f, for the reception of 45 ribs g on a box, J, which is open at the rear end, and contains a spring adapted to bear up-

on one of the nuts h, whereby the clip is secured, the front end of the spring being acted upon by a nut, m, which is adapted to a screw-stem, n, swiveled to the front end of the box, 55 the nut being guided in the box and prevented from turning by means of a lug, s, adapted to a groove, t, in the bottom of the box. (See Figs. 2 and 5.) Any desired form of lug or bearing for the spring may be used in place 60 of the nut h; but the latter is convenient, and its use is therefore preferred. The box J is further guided in the block F by means of projections p, which bear upon the under side of similar projections, q, on the block; and on 65 each of said projections p is a lug, w, adapted to bear upon the short arm of one of the levers G, as shown in Fig. 1.

In fitting the coupling together the block F and the parts carried thereby are first applied 70 to the clip, the screw-stem n being loosened and the levers G retracted, as shown by dotted lines in Fig. 1. The thill is then applied and the pin d inserted, after which the notched arms of the levers G are applied to the grooved 75 ends of the pin d, and the screw-stem n is turned so as to compress the spring and cause the box J to be thrust forward. The lugs w are thus brought into contact with the short arms of the levers G, and the disengagement of the notched 80 long arms of said levers from the grooved ends of the pin d is prevented, further movement of the box J being then transmitted to the block F, which is caused to bear upon the eye a of 85 the thill-iron with any desired amount of pressure, and thus effectually prevent any rattling of said thill.

The pin d may have the portion x, which is adapted to the opening in one of the ears b, square, as shown in Fig. 4, or beveled, as shown 90 in Fig. 6, so as to insure the adjustment of the pin to its proper lateral position.

By adapting the sliding box J to guides in the block F, I render the device more compact than those previously patented by me, and am 95 enabled to protect the spring, the device, moreover, being easier to apply and adjust than either of the others.

In some cases where it is only desired to prevent rattling of the thill, the levers G may be 100 dispensed with, and the thill may be fastened by the usual transverse pivot-bolt and nut, the

box J in this case being secured to the block F, or adapted to bear against lugs on the same, so that on tightening the screw-stem n the block will be caused to bear firmly against the eye a.

5 Instead of a coiled spring, a block of rubber or other elastic material may be used; but the coiled spring is preferred.

I claim as my invention—

1. The combination of the clip, thill-iron, and 10 pivot-pin, having grooved ends, with the bearing-block F, and the notched retaining-levers G G, hung to the block and adapted to the opposite grooved ends of the pin, as set forth.

2. The combination of the thill-eye and pivot-pin with the block F, the sliding box J, 15 having a spring, M, and the bearing h, as set forth.

3. The combination of the thill-eye and pivot-pin with the block F, the sliding box J, 20 having a spring, M, and adjusting-screw n, and with the bearing h, as set forth.

4. The combination of the thill-eye and pivot-pin, the block F and its notched levers G,

the sliding box J and its lugs w, the spring M, and the bearing h, as set forth.

5. The combination of the thill-eye and pivot-pin, the block F and its notched levers G, 25 the sliding box J, having lugs w, the spring M, the adjusting-screw n, and the bearing h, as set forth.

6. The combination of the block F, the sliding box J, the spring M, the nut m, and the screw-stem n, swiveled to the box and adapted to the nut, as set forth.

7. The combination of the block F, the sliding box J, having a groove, t, the spring M, the nut m, having a lug, s, and the screw-stem n, as set forth.

In testimony whereof I have signed my name to this specification in the presence of two subscribing witnesses.

GEORGE W. HASKELL.
